AUTOMATIC CONTROLLER

Hermon L. Van Valkenburg, Wauwatosa, Wis.,
assignor to Square D Company, Detroit, Mich.,
a corporation of Michigan

Application December 7, 1934, Serial No. 756,424

27 Claims. (Cl. 172—288)

This invention relates generally to automatic electric circuit controllers and more particularly to automatic motor starters of the current limit type for starting direct current motors.

5 Direct current automatic starters of the current limit type are well adapted for several classes of service especially those in which there is a high inertia load. This type of starter, however, has the disadvantage that the accelerating 10 contactors will not function if the load on the motor exceeds that for which the lockout coils have been adjusted. In other words if the accelerating units have been so adjusted that they will cut out resistance when current drops to a given 15 value they will not operate if for some reason the current will not fall below this current value. One example of an instance wherein this trouble may occur is with motors driving grinders in which a very heavy load may be applied to the grinding-wheel before the motor has been fully 20 brought up to speed. It is obvious that this same trouble may occur for many other reasons in actual practice. Under such conditions the starting resistance will be left in circuit and would be likely to burn out.

25 Aside from the above difficulty, the characteristics of the current limit starter are very desirable as the motor will be brought up to full speed in the shortest possible time consistent with a given accelerating current. For instance, 30 if a starter is furnished with a resistance so proportioned as to permit a maximum of 100% overload in starting, the motor will then come up to speed in the shortest possible time without exceeding this in-rush current.

35 To correct the disadvantage above set forth in the current limit starter the invention in one aspect consists in providing a time limit relay for each accelerating unit which will short-circuit the lockout coil after a predetermined interval of 40 time if the accelerating unit does not function.

Another object of this invention is to provide an automatic starter embodying combined current and time limit acceleration.

45 Another object of this invention is to provide an automatic starter operating through current limit acceleration with a relay which will shunt the lockout coil after a predetermined time interval.

50 A further object of this invention is to provide an automatic starter in which the lockout coil is in series with a self-heating thermal relay which operates to shunt out the lockout coil after a predetermined time interval.

55 Another object of this invention is to provide

an automatic starter of the current limit type using a starting resistance with a protective circuit to prevent burning out of said resistance.

A further object of this invention is to provide an automatic starter of the current limit type in which the lockout coils are connected in shunt across the successive steps of starting resistance and in which a thermal relay is connected in series with the lockout coil, the thermal relay operating to close a shunt circuit for the lockout coil.

Another object of this invention is to provide an improved method of starting motors.

Still another object of this invention is to provide an improved current limit relay having a positive time limit operation.

Further objects and features of the invention will be readily apparent to those skilled in the art from the following specification and the appended drawing illustrating certain preferred 20 embodiments of the invention in which:

Figure 1 is a schematic wiring diagram showing one embodiment of this invention particularly adapted for use with small motors.

Figure 2 is a schematic wiring diagram of another embodiment of this invention particularly suited for large motors.

Referring now particularly to the embodiment of the invention as shown schematically in Figure 1, the numerals 1 and 2 designate line terminals. A motor 3 has one side of its armature connected to terminal 1 by conductor 4. The shunt field 5 is connected across the line by conductors 6 and 7, conductor 6 being connected directly to line 1 through conductor 4; conductor 7 30 being connected to one side of main contactor 8 through a connection 9. The main contactor 8 has an actuating coil 11 connected across the line terminals by conductors 12 and 13 through a switch 14. The other side of the armature of 40 motor 3 is connected through a conductor 15 to contact 16 and thence to one side of the starting resistance 17 which, as shown, embodies two steps 18 and 19. The other end of starting resistance 17 is connected by conductor 21 to the lockout coil 45 22 of the first accelerating step of the starter. The other side of the lockout coil 22 is connected by conductor 23 to one leg of a U-shaped bimetallic member 24, the other leg of which is connected to one side of the main contactor through 50 the connection 9. The tip of bimetallic member 24 carries a contact 25 disposed adjacent to a stationary contact 26 which is connected through conductor 27 to the same side of lockout coil 22 as the conductor 21. It is thus seen that a shunt 55

circuit across the lockout coil 22 is provided through conductor 23, one leg of bimetal 24, contacts 25 and 26 and conductor 27. This shunt circuit is normally open and is closed by the flexure of the thermostatic member 24 as it is heated by the starting current. The main contactor 8 embodies a stationary contact 28 connected to line terminal 2 and a movable contact 29 attracted into engaged position with contact 28 by operating coil 11. A movable contact 31 attached to contact 29 and moving therewith is provided. This contact engages a stationary contact 32 to which is connected conductor 33 leading to one side of the shunt operating coil 34. The other side of operating coil 34 is connected by conductor 35 to switch 14. The coils 34 and 22 constitute a differential solenoid surrounding an armature 36 which carries a conducting member 37 adapted to bridge contacts 38 and 39. Contact 38 is connected by conductor 41 to conductor 9 and thence to main contact 8. Contact 38 is also connected by conductor 42 to contact 43 which is disposed adjacent to contact 16. Contacts 16 and 43 are adapted to bridge by a conducting member 44 carried by armature 45 under the action of operating coil 46 and lockout coil 47. Operating coil 46 is connected at one side by conductor 48 to switch 14. The other side of the operating coil 46 is connected by conductor 49 and the short flexible lead 51 to conducting member 37. Lockout coil 47 is connected at one side by conductor 52 to resistor 17 at the junction between steps 18 and 19. The other side of lockout coil 47 is connected through conductor 53 to one leg of bimetallic member 54, the other leg of which is connected by conductor 55 to contact 39. The tip of the bimetallic member 54 carries a contact 56 adapted to engage a stationary contact 57 disposed adjacent thereto and connected by a wire 58 to the same side of the lockout coil as conductor 52.

The operation of the starter above described is as follows:

Switch 14 is manually closed thus energizing operating coil 11 and closing main contactor 8. This energizes operating coil 34 through contacts 31 and 32, conductor 33, coil 34, conductor 35, switch 14 and conductor 13 to the opposite line terminal. At the same time a circuit through the motor armature is initiated from line terminal 2, contacts 28 and 29, conductor 9, bimetal 24, conductor 23, lockout coil 22, conductor 21, resistance 17, conductor 15, the armature of motor 3, and conductor 4 to line terminal 1. The circuit through shunt field 5 is completed through contacts 28 and 29, conductor 9, conductor 7, shunt field 5, conductor 6 and conductor 4 to line terminal 1. If the motor 3 starts and builds up speed, the starting current will rapidly decrease and the lockout coil 22 will no longer be sufficient to counteract the tendency of operating coil 34 to move armature 36 which then moves bridging member 37 into engagement with contacts 38 and 39 cutting out step 18 of the starting resistance 17. This also shunts out the circuit through lockout coil 22 and bimetal 24. The circuit through the motor armature then runs from line 9 to line 41 thence through contact 38 and bridging member 37, contact 39, conductor 55, bimetal 54, conductor 53, lockout coil 47, conductor 52, step 19 of the starting resistance, conductor 15, armature of motor 3, conductor 4 to the opposite line terminal. Operating coil 46 is now connected across the line through main contactor 8, conductor 9, conductor 41, contact 38, bridging mem-

ber 37, flexible lead 51, conductor 49, operating coil 46, conductor 48 to switch 14 and conductor 13 to the opposite side of the line. The operation of this second step of the acceleration is similar to that previously described. If the motor continues to build up the speed, the armature current will decrease until lockout coil 47 no longer counteracts the action of operating coil 46 whereupon bridging member 44 will complete a circuit through contacts 16 and 43 connecting the motor directly to the line terminals and shunting out bimetal 54 and lockout coil 47. The operation of the starter as above defined has been pure current limit which is the normal operation of the starter. If the motor 3 should not start or build up in speed sufficiently to reduce the armature current to a point where lockout coil 22 will no longer counteract the closing action of operating coil 34, current will continue to flow through resistor 17 until bimetal 24 becomes heated to a point where it flexes and engages contacts 25 and 26. This closes the shunt across lockout coil 22 whereupon operating coil 34 moves armature 36 and member 37 into their bridging position regardless of the value of the current flowing through the motor armature thus cutting out step 18 of resistance 17. If the motor still does not start or if the armature current is still high enough to prevent operating coil 46 from closing contacts 43 and 16, current will continue to flow through step 19 of the starting resistance until bimetal 54 causes contacts 56 and 57 to engage whereupon lockout coil 47 will be shunted out and bridging member 44 will be operated to cut out resistance step 19 and connect motor directly to the line. The latter described operation is an abnormal one which is intended to function only when the armature current does not decrease quickly enough to a value where the lockout coil becomes ineffective. This provides for a positive time limit acceleration by cutting out the steps of the starting resistance after a predetermined time interval if the armature current is too high to permit of normal current acceleration. This prevents a burning up of resistance 17 by positively shunting steps 18 and 19 out of the motor circuit regardless of the values of the armature current.

The starter as just described has obvious advantages over the current limit starter or the time limit starter. In the current limit starter, if the motor current does not decrease to a predetermined value the starting resistance will be left in the circuit until it burns out and is destroyed. In the time limit starter the periods of operation of the resistance steps are fixed and thus in normal operation a greater time interval will be taken in starting the motor than is necessary. In the starter as above described the time required to start the motor will always be at a desired minimum since under normal operating conditions the current limit portion of the starter will operate to cut out resistance and bring the motor up to speed in the shortest time interval corresponding to their current settings and it is only when the armature current does not decrease to the set value that the time limit portion of the starter operates to positively shunt out steps of the starting resistance. While the starter is illustrated and described as employing a bimetal 24, it is obvious that any other type of time limit relay could be substituted therefor although the bimetal is preferred since its time of operation is dependent upon the current flowing therethrough and inherently embodies the additional protective fea-

ture of cutting out the resistance with a time interval which will depend to some extent on the value of the current flowing therethrough. However, other time limit relays could be substituted therefor to secure the desired current and time limit features and as examples thereof there could be used a magnetic relay with a dash pot or an indirectly heated thermal relay or any other form of time limit relay.

10 Figure 2 illustrates another embodiment of the invention peculiarly adapted for larger motors. Like reference numerals refer to parts similar to those shown in Figure 1. In this figure resistance 17 is divided into three accelerating steps; three 15 combined current and time limit relays being provided to cut out these steps. In this embodiment the thermal element and lockout coils do not carry the full motor current but are connected in parallel with the corresponding steps of the starting resistance and their circuits contain an added resistance to control the division of currents between the starting resistance and the control circuits. In this figure there are line terminals 1 and 2 and a main contactor 8 having stationary 20 and movable contacts 28 and 29, an operating coil 11 and auxiliary contacts 31 and 32. A switch 14 is provided, one side of which is connected to line terminal 1, by conductor 13, the other side of which is connected to operating coil 11 by conductor 12 and to the operating coils 34, 46' and 46 for the bridging contactors through conductors 35 and 48' and 48. The other side of coil 34 is connected to contact 32 by conductor 33. The other side of coil 46' is connected to bridging member 37 by conductor 49' and flexible lead 51'. The opposite side of coil 46 is connected to conducting member 44' by conductor 49 and flexible lead 51. The lockout coils and thermal elements are connected in series with each other and with resistances 61, 62 and 63. Lockout coil 22 is connected in series with bimetal 24 and resistor 61, the bimetal controlled shunt circuit 23, 25, 26 and 27 being provided for the lockout coil 22. This circuit is connected at one side to the line 2 through conductor 9 and the main contactor 8. The opposite side of this control circuit is connected to contact 39 and thence to the end of the first accelerating step 18 of the starting resistance. The control circuit is thus placed in parallel with step 18 of the starting resistance. The control circuit for the second accelerating step embodying the lockout coil 47', bimetal 54' and resistance 62 is connected at one side to conductor 49' and at the other side to contact 16' thus placing it in parallel with the second step 19' of the starting resistance. The bimetal controlled shunt circuit 53, 56, 57' and 58' is provided for lockout coil 47'. The control for the third accelerating step embodying lockout coil 47, bimetal 54, resistance 63, 60 is connected at one side to conductor 49 and at its opposite side to conductor 15 leading to the motor and is thus placed in parallel with the last step 19 of the starting resistance. The lockout coil 47 is provided with the bimetal controlled shunt circuit 53, 56, 57 and 58. The operation of the starter shown in Figure 2 is similar to that shown in Figure 1 and it is thought unnecessary to take the space necessary to describe it in detail since it is readily apparent from the description of the 65 operation of the starter in Figure 1; the only difference being that here there are shown three accelerating steps and each control circuit carries only a fraction of the total motor current since each is connected in parallel with the corresponding step of the starting resistance. The

parallel arrangement of Figure 2 is particularly adapted to large size motors due to practical limitations in the size of the thermal elements and in the current carrying capacity of the short-circuiting contacts of the thermal relay.

5 While Figure 1 is showing two accelerating steps and Figure 2 is disclosing three accelerating steps it is obvious that in either form any number of accelerating steps may be used to secure the desired starting characteristics.

10 While certain preferred embodiments of the invention have been specifically disclosed, it is understood that the invention is not limited thereto as many variations will be readily apparent to those skilled in the art and the invention 15 is to be given its broadest possible interpretation within the terms of the following claims:

1. The method of starting a motor which comprises connecting said motor to the line through a starting resistance, short-circuiting said starting resistance if and when the motor current decreases to a predetermined value, and short-circuiting said starting resistance after a predetermined time interval when the motor current fails to decrease to said value.

2. The method of starting a motor which comprises connecting the motor to a line through a starting resistance, short-circuiting said starting resistance if the motor current decreases to a predetermined value within a predetermined 20 time interval, and short-circuiting said starting resistance at the end of said time interval regardless of the failure of the motor current to decrease to said value.

3. An electrical relay comprising relatively 25 movable contacts, means for operating said contacts, current responsive means restraining operation of said contacts and means for automatically rendering said restraining means ineffective.

4. In an automatic starter for electric motors, a starting resistance, an accelerating contactor adapted to shunt out at least a part of said starting resistance, an operating coil for said contactor, current responsive means restraining 45 operation of said contactor, and means for automatically rendering said restraining means ineffective.

5. In an automatic starter for electric motors, a starting resistance, a contactor adapted to 50 shunt out at least a part of said starting resistance, a shunt coil normally urging said contactor to closed position, a lockout coil responsive to the motor current normally urging said contactor to open position and a time limit relay 55 connected to short-circuit said lockout coil when the contactor does not close after a predetermined time interval.

6. In an automatic starter for electric motors, a starting resistance, an accelerating contactor 60 adapted to cut out at least a part of said starting resistance and means for actuating said contactor normally responsive to a predetermined value of starting current and actuating said contactor after a predetermined time interval when the starting current has failed to decrease to said value.

7. In an automatic starter for electric motors, a starting resistance and an accelerating contactor for cutting out said starting resistance, means for operating said accelerating contactor when the starting current decreases to a predetermined value, said means operating said accelerating contactor after a predetermined time 75

- interval regardless of the failure of the starting current to decrease to said value.
8. An automatic controller for electric circuits comprising relatively movable contacts, an operating coil for biasing said contacts toward closed position, a current responsive lockout coil for biasing said contacts toward open position, a bimetallic element connected in series with said lockout coil, a contact carried by said bimetallic element, a second contact disposed adjacent to said first mentioned contact and in the path of movement thereof, said second contact being connected to the side of the lockout coil opposite to the one connected to the bimetallic member, the bimetallic element flexing to close the contacts and short-circuit the lockout coil when the relay fails to operate after predetermined time interval.
9. In an automatic starter for electric motors, a starting resistance divided into a plurality of accelerating steps, a plurality of accelerating contactors successively short-circuiting said steps, each contactor including an operating coil for biasing said contactor toward closed position, a lockout coil responsive to the current through the starting resistance for biasing said contactor toward open position, and a time limit relay short-circuiting said lockout coil when its associated contactor fails to function within a predetermined time interval.
10. An automatic starter for electric motors comprising a starting resistance, an accelerating contactor adapted to short-circuit at least a part of said resistance, an operating coil for biasing said contactor toward closed position, a current responsive lockout coil for biasing said contactor toward open position, a bimetallic element, an auxiliary resistance, said lockout coil, bimetallic element and auxiliary resistance being connected in series with each other and in parallel with at least a part of the starting resistance and a shunt for said lockout coil controlled by said bimetallic element.
11. In an automatic starter for electric motors, a starting resistance, means for shunting said resistance from the circuit after a predetermined time interval, said means shunting said resistance before the expiration of said time interval when the motor current decreases to a predetermined value.
12. An automatic starter for electric motors comprising a starting resistance, means for shunting at least a part of said resistance when the motor current decreases to a predetermined value, and means operating to effect shunting of at least a part of said resistance after a definite time interval upon the failure of the motor current to decrease to said value.
13. An automatic starter for electric motors comprising a starting resistance, means responsive to the current through the motor for shunting at least a part of said resistance when the current decreases to a predetermined value and a time delay relay operating to effect shunting of at least a part of said resistance after a definite time interval upon the failure of the motor current to decrease to said value.
14. In an automatic starter for electric motors, a starting resistance, a contactor connected to shunt at least a part of said resistance from the motor circuit, means biasing said contactor toward closed position, a current responsive coil biasing said contactor to open position, and a time limit relay operating to short-circuit said coil if contactor does not operate after a definite time interval.
15. An automatic controller for electric circuits comprising relatively movable contacts, means for biasing said contacts toward closed position, current responsive means for biasing said contacts toward open position, a normally open shunt for the current responsive means, and means to close said shunt circuit when said contacts fail to close after a definite time interval.
16. An automatic controller for electric circuits comprising relatively movable contacts, an operating coil for biasing said contacts toward closed position, a current responsive lockout coil for biasing said contacts toward open position, a normally open shunt circuit for said lockout coil and a current responsive element connected in series with said lockout coil for closing said shunt circuit.
17. An automatic controller for electric circuits comprising relatively movable contacts, an operating coil for biasing said contacts toward closed position, a current responsive lockout coil for biasing said contacts toward open position, a thermostatic element connected in series of said lockout coil, and a shunt circuit for said lockout coil closed by said thermostatic element.
18. In an automatic controller for electric circuits comprising relatively movable contacts, an operating coil for biasing said contacts toward closed position, a current responsive lockout coil for biasing said contacts toward open position, and a bimetallic element connected in series with said lockout coil, said element operating to short-circuit the lockout coil when the contacts fail to close after a definite time interval.
19. An automatic starter for electric motors comprising a starting resistance, an accelerating contactor adapted to shunt out at least a part of said starting resistance, an operating coil for biasing said contactor toward closed position, a current responsive lockout coil for biasing said contactor toward open position, an auxiliary resistance, said lockout coil being connected in parallel with at least a part of said starting resistance through an auxiliary resistance, and a time limit relay short-circuiting said lockout coil when said contactor fails to close after a definite time interval.
20. In an automatic starter for electric motors, a starting resistance adapted to be connected in series with a motor armature, and means for automatically shunting out at least a portion of said resistance, said means functioning when the motor current decreases to a predetermined value within a definite time interval, said means functioning at the end of said interval regardless of the failure of the motor current to decrease to said value.
21. An automatic starter for electric motors, comprising a starting resistance, a normally open shunt circuit for at least a part of said resistance, a contactor for closing said shunt circuit, and means for operating said contactor when motor current decreases to a predetermined value, said means operating said contactor at the end of a definite time interval when the motor current fails to decrease to said value.
22. An automatic starter for electric motors comprising a starting resistance, a contactor operating to shunt out at least a part of said starting resistance, an operating coil for biasing said contactor toward closed position, a current responsive lockout coil for restraining operation of said contactor, a thermostatic element con-

nected in series with said lockout coil and a shunt circuit for said lockout coil adapted to be closed by said thermostatic element.

23. An automatic starter for electric motors comprising a starting resistance, a contactor operating to shunt out at least a part of said starting resistance, a shunt coil for operating said contactor, a current responsive lockout coil for preventing operation of said contactor, a bimetallic element connected in series with said lockout coil, said element short-circuiting said lockout coil when the contactor fails to operate after a definite time interval. 10

24. An automatic starter for electric motors comprising a starting resistance divided into a plurality of accelerating steps, a plurality of accelerating contactors for successively short-circuiting said steps, each contactor including a shunt operating coil, a current responsive lockout coil and a time limit relay for short-circuiting said lockout coil when the associated contactor fails to function within a definite time interval after being energized, the closing of each contactor energizing the shunt coil, lockout coil, and time limit relay of the next succeeding contactor. 20

25. An automatic starter for electric motors comprising a starting resistance divided into a plurality of accelerating steps, a plurality of accelerating contactors for successively short-circuiting said steps, each contactor including a shunt operating coil, a current responsive lock- 30

out coil and a time limit relay for short-circuiting the lockout coil when the associated contactor fails to operate within a definite time interval after being energized, said lockout coil and time limit relay being connected in series with each other and in parallel with the associated step of the starting resistance, the closing of each contactor operating to energize the operating coil, lockout coil, and time limit relay of the next succeeding contactor in the accelerating series. 10

26. The method of starting an electric motor through a starting resistance which is shunted from the circuit after the starting period to connect the motor directly to the line, which comprises connecting a motor to a line through a 15 starting resistance and shunting said resistance from the motor circuit at the minimum time consistent with a desired maximum overload and, failing decrease to said maximum overload, after 20 a maximum set time.

27. The method of starting an electric motor to secure a starting time having the minimum value consistent with a desired maximum overload and a maximum set value which comprises connecting said motor to a line through a starting resistance and shunting at least a part of said resistance from the circuit if and when the motor current decreases to a predetermined value and, failing such decrease, after a definite time 30 interval independent of the value of the current. 25
